DISPENSER FOR ROLLS OF SHEET MATERIAL

Lehyman J. Bastian, Riddlewood, Pa.

Application October 28, 1955, Serial No. 38,607

Term of patent 14 years

(Cl. D4—3)

Fig. 1.

Fig. 3.

Fig. 2.

Figure 1 is a perspective view of a dispenser for rolls of sheet material embodying my new design.

I claim:

The ornamental design for a dispenser for rolls of sheet material, as shown.
